His Attorney.

UNITED STATES PATENT OFFICE

127,367

DESIGN FOR A CLOCKCASE

Leo Ivan Bruce, Framingham, Mass., assignor to General Electric Company, a corporation of
New York

Application December 31, 1940, Serial No. 97,740

Term of patent 7 years

To all whom it may concern:

Be it known that I, Leo Ivan Bruce, a citizen of the United States, residing at Framingham, in the county of Middlesex, State of Massachusetts, have invented a new, original, and ornamental Design for a Clockcase of which the following is a specification, reference being had to the accompanying drawing, forming a part thereof,

The figure is a front perspective view of a clockcase showing my new design.

I claim:

The ornamental design for a clockcase as shown.

LEO IVAN BRUCE.
